(57) **CLAIM**

We claim the ornamental design for an elastic band neck exerciser, as shown and described.

DESCRIPTION

FIG. 1 is a perspective view of an elastic band neck exerciser, showing our new design in a stretched configuration;

FIG. 2 is a left-side elevational view thereof;

FIG. 3 is a right-side elevational view thereof;

FIG. 4 is a top plan view thereof, the bottom plan view being a mirror image thereof;

FIG. 5 is a front elevational view thereof;

FIG. 6 is a rear elevational view thereof; and,

FIG. 7 is a perspective view thereof, illustrated in a relaxed position.

The broken lines showing a door and a person in FIG. 1 depict environmental matter and form no part of the claimed design.
